STEERING COLUMN ATTACHED ARMREST

Allen A. White, Peabody, Kans.

Application June 12, 1953, Serial No. 25,464

Term of patent 14 years

(Cl. D14—6)

To all whom it may concern:

Be it known that I, Allen A. White, a citizen of the United States and resident of Peabody, in the county of Marion and State of Kansas, have invented a new, original, and ornamental Design for a Steering Column Attached Armrest, of which the following is a specification, reference being had to the accompanying drawing, forming a part hereof.

In the drawing:

Figure 1 is a top plan view of a steering column attached armrest, showing my new design; and

Figure 2 is a side elevational view of the design shown in Figure 1.

I claim:

The ornamental design for a steering column attached armrest, substantially as shown.
